BOLSTER SUPPORTING SPRING UNIT

Donald F. Sproul, Chicago, Ill., assignor to Cardwell-Westinghouse Company, a corporation of Delaware

Application January 16, 1936, Serial No. 59,427

9 Claims. (Cl. 267—9)

This invention relates to resilient friction devices and more particularly bolster springs or supporting units for railway bolsters.

One of the objects of the invention is the provision of a new and improved spring unit for supporting railway truck bolsters having novel means for frictionally resisting the compression of the unit.

Another object of the invention is the provision of a new and improved bolster supporting spring unit having novel means for frictionally resisting the compression of the spring and for limiting the expansion thereof.

A further object of the invention is the provision of a new and improved bolster supporting unit that is simple in construction, efficient in operation, composed of few parts and that may be readily installed in the conventional bolster supporting spring assembly.

Other and further objects and advantages of the invention will appear from the following description taken in connection with the accompanying drawing in which

Fig. 1 is a side elevation of a railway truck showing the invention in position beneath the bolster of the truck with parts broken away;

Fig. 2 is a vertical section of the device on line 2—2 of Fig. 3;

Fig. 3 is a horizontal section on line 3—3 of Fig. 2;

Fig. 4 is a perspective view of the friction shoes; and

Fig. 5 is a perspective view of one of the friction members.

It is common practice to support the bolsters of railway trucks by a nest of helical springs beneath each end of the bolster. These springs are free acting and unless means be provided for resisting free vibration of the springs, the vibration thereof, under certain conditions, may continue to build up, as when the natural period of vibration of the springs synchronizes with the movement of the truck over the rail joints, or with the vertical vibration of the truck due to flat surfaces on the surfaces of the wheel treads. These vibrations have been known to build up to such a stage as to cause serious injury as when they cause the springs to go solid on compression under heavy load, thereby causing breakage of the truck frames; and with light loads causing derailment of the wheels.

The present invention seeks to eliminate this difficulty by the provision of new and improved means for dampening the vibrations of the free-acting springs.

Referring now to the drawing, the reference character 8 designates a railway car truck having a bolster opening 10 in the side frame thereof through which one end of the bolster 11 extends. The bolster 11 is mounted to slide vertically in the opening in the usual manner. As is common in such constructions, a spring assembly or nest of springs 12 is interposed between the bolster and a spring plank 13 carried by the side frame. Since the details of the truck frame and truck 10 constitute no part of the present invention, it is not thought necessary to further illustrate or describe the same.

The present device or spring unit 14 is of such dimensions that it may be substituted for one of the conventional bolster supporting helical springs 15. This spring supporting unit 14 comprises the friction members 16 and 17, each of which has a cap or base portion 18 and a concentric cylindrical portion 19 extending outwardly therefrom, surrounded by a flange 40. Since the friction members 16 and 17 are duplicates, the lower one only need be described.

The base portion 18 is provided with a center opening 21 which is adapted to receive the conventional positioning lug on the spring plate or spring plank for positioning the spring unit. The cylindrical portion 19 extends about the opening 21 and has its upper or open end provided with a pair of beveled or wedging faces 22 and 220 on its inner surface, each facing inwardly and upwardly as shown in Figs. 2 and 5 of the drawing. These wedging faces may be considered as segments of cylinders arranged at an angle to each other as shown in Figs. 2 and 3. An annular portion of the inner surface of the cylindrical portion 19 is removed, that is, an annular recess 20 is provided, to form an annular shoulder 23 at the base of the inclined or wedging faces 22 and 220, which are adapted to be engaged by suitable flanges or lugs on the friction shoes for limiting the expansion of the unit as will presently appear.

A pair of friction shoes 24 and 25, each having what may be termed oppositely arranged friction surfaces, that is, an upper inclined wedging face 26 facing outwardly and upwardly, and a lower inclined wedging face 27 facing outwardly and downwardly, Fig. 4, is interposed between the friction members 16 and 17 in such a manner that the wedge or inclined faces 26 and 27 engage the corresponding wedge faces 22 and 220 respectively, of said friction members. Each of the friction shoes 24 and 25 are provided at their ends with flanges 28 and 29 which are adapted 55

to engage the shoulders 23 on the friction members for limiting the expansion of the unit. Each of the shoes 24 and 25 have their outer surfaces curved transversely to correspond with the curvature of the inner surfaces of the wedge faces of the friction members.

Suitable means are provided for forcing the shoes into frictional contact with the wedge faces of the wedge members. As shown, a single helical 10 spring 30 is employed for this purpose and is arranged transversely of the axis of the unit. Each of the shoes is preferably provided with a spring seat 31 for positioning the spring.

The unit is provided with resilient means for assisting in supporting the load and also for returning the parts to expanded position upon release after the unit has been compressed. As 15 shown, a helical spring 32 is employed for this purpose. This spring surrounds the friction members and engages the flanges 40.

It will thus be seen that upon compression of the gear, the shoes will be forced inwardly against the spring 30, and its increasing resistance to compression as the unit is compressed will cause 20 an increasing friction between the shoes and the friction surfaces 22 and 220. Since the ends of the shoes are free to move radially and the spring is arranged along the transverse axis of the two shoes, there will be substantially the same frictional resistance between the two ends of the 25 shoes and the cooperating friction surfaces 22 and 220. Upon release of the gear, the spring 32 expands the gear until the flanges 28 and 29 engage the shoulders 23 which limit further expansion.

Means are provided for taking the overload for 30 protecting the spring 32 from going solid when the unit is compressed. This may be accomplished in any one of three ways. The friction 35 shoes 24 and 25 may be of such length that they will engage the bases of the friction members 16 and 17 before the inner ends of the friction members 16 and 17 engage or vice versa. Or, if desired, these parts may all engage simultaneously, 40 thus making an exceedingly solid column for taking the overload when the unit is compressed. The latter arrangement is shown.

Instead of the single transverse spring 30 for 45 forcing the shoes apart into frictional engagement with the friction surfaces 22 and 220 of the friction members 16 and 17, a plurality of springs may be employed for this purpose.

It is thought from the foregoing taken in connection with the accompanying drawing that 50 the construction and operation of my device will be apparent to those skilled in the art and that changes in size, shape, proportion and details of construction may be made without departing from the spirit and scope of the appended claims.

60 I claim as my invention:—

1. A cylindrical base member having a flange extending about its lower portion, a cylindrical bolster supporting member having a flange extending about its upper end, the adjacent ends 65 of said cylindrical members having their inner surfaces inclined outwardly to form wedging surfaces comprising segments of cylinders, a plurality of shoes having inclined friction surfaces in the form of segments of cylinders engaging the 70 inclined surfaces of said members, resilient means extending transversely to said shoes and tending to separate the same, and a spring surrounding said members and engaging said flanges for resisting the compression of said unit.

2. In a truck bolster supporting spring unit,

a pair of cylindrical friction members having flanges on their outer ends, each member having on the inner surface of its inner end inclined wedging surfaces at opposite sides of said member, curved in cross-section, a pair of friction 5 shoes having wedge faces on their ends engaging said wedging surfaces, each of said shoes having spring seats on its inner side walls between the ends thereof, spring means engaging said seats, and a spring surrounding said cylindrical members and engaging said flanges.

3. A bolster supporting unit, comprising a pair of friction members, each having a base and a cylindrical portion extending inwardly from the base, each cylindrical portion having its interior 10 surface at its open end flared outwardly to form a wedging friction surface comprising a segment of a cylinder, a plurality of shoes, each having a pair of wedging surfaces curved transversely and engaging the wedging surfaces of the friction 15 members, resilient means resiliently forcing said shoes radially outwardly into frictional contact with the friction surfaces of said friction members, and a spring surrounding said shoes and cylindrical portions and engaging said bases for 20 returning the parts after compression.

4. In a bolster supporting unit, a pair of base members spaced apart, each base member having a flange extending about the same and an inwardly extending cylindrical member having 30 inclined friction surfaces comprising a segment of a cylinder, a plurality of friction shoes each having inclined friction surfaces corresponding to the friction surfaces of said cylindrical members 35 at each end thereof engaging the friction 40 surfaces of said cylindrical members, cooperating flanges and shoulders on said shoes and base members for limiting the separation of said base members, resilient means for forcing said shoes radially outwardly, and a spring extending about 45 said cylindrical members and engaging said flanges for resisting the compression of the unit.

5. In a bolster supporting unit, a pair of cylindrical friction members having inclined friction surfaces, a pair of shoes each tapered toward 45 each end to form double wedge surfaces for telescoping into and frictionally engaging the inclined friction surfaces of said members, resilient means comprising a helical spring arranged transversely to the axis of said unit for forcing 50 said shoes outwardly into frictional engagement with said members, spring means surrounding said shoes and friction members for resisting the compression of said unit, and interlocking means 55 between said shoes and friction members for limiting the separation of said members.

6. In a bolster supporting unit, a pair of hollow friction members each having an abutment at one end and having its inner surface at its other end inclined to form segmental cylindrical 60 wedging surfaces, a flange extending about the outer end of each member, a pair of shoes each tapered on its outer surface toward each end frictionally engaging the wedging faces of said friction members, said shoes having projections 65 extending radially outwardly for engaging said abutments for limiting the expansion of said unit, resilient means surrounding said shoes and members and engaging said flanges for returning the parts to normal position after compression, and 70 resilient means for normally yielding forcing said shoes diametrically outward into frictional resistance with said members.

7. In a bolster supporting unit, a pair of hollow friction members each having an abutment 75

- 5 at one end and having its inner surface at its other end inclined to form a segmental cylindrical wedging surface, a pair of shoes each tapered on its outer surface toward each end frictionally engaging the wedging faces of said friction members, said shoes having projections extending radially outwardly for engaging said abutments for limiting the expansion of said unit, resilient means for returning the parts to normal 10 position after compression, a helical spring extending transversely to the axis of said unit for yieldingly forcing said shoes into frictional resistance with said members, and means for limiting the compression of said resilient means.
- 15 8. In a bolster supporting unit, a pair of cylindrical friction members having inclined friction surfaces, each of said surfaces being a segment of a cylinder, shoes frictionally engaging

the inclined friction surfaces of said members, resilient means interior of said shoes for forcing said shoes into frictional engagement with said members, and spring means for returning the parts to normal position after compression. 5

9. In a truck bolster supporting spring unit, a pair of cylindrical friction members having wedge surfaces comprising segments of cylinders on the interior surface of their adjacent ends, a pair of wedge shoes, each having oppositely arranged wedging faces curved transversely of the shoes, a single transversely arranged spring engaging the central portions of said shoes and extending transversely of the shoes, and resilient means for restoring the parts to normal position 10 after compression. 15
